Primary Examiner — Catherine A Tuttle(74) *Attorney, Agent, or Firm* — Loeb & Loeb LLP(57) **CLAIM**

The ornamental design for a fidget spinner, as shown and described.

DESCRIPTION

FIG. 1 is a perspective view of a fidget spinner showing my new design;

FIG. 2 is a top view thereof;

FIG. 3 is a bottom view thereof;

FIG. 4 is a right side elevational view thereof;

FIG. 5 is a left side elevational view thereof;

FIG. 6 is a front elevational view thereof; and,

FIG. 7 is a back elevational view thereof.

The broken lines shown in the drawings are for the purpose of illustrating portions of the fidget spinner that form no part of the claimed design.

1 Claim, 5 Drawing Sheets(56)
